UNITED STATES PATENT OFFICE.

RICHARD FRANKLIN AMERICA, OF PHILADELPHIA, PENNSYLVANIA.

STREET AND STATION INDICATOR.

1,147,590.

Specification of Letters Patent. Patented July 20, 1915.

Application filed September 23, 1914. Serial No. 863,179.

To all whom it may concern:

Be it known that I, RICHARD F. AMERICA, a citizen of the United States, residing at 1712 Ellsworth street, Philadelphia, in the county of Philadelphia and State of Pennsylvania, have invented new and useful Improvements in Street and Station Indicators, of which the following is a specification.

This invention relates to station indicators, the object in view being to produce a device which is manually controlled and by means of which stations, streets and other places may be visually indicated to the occupants of a car in which the indicator is located.

A further object of the invention is to provide a novel arrangement of drums upon which the web or ribbon containing the desired information is wound so as to provide for constantly taking up slack in the web, together with novel operating mechanism whereby the web may be propelled in either direction so that the streets or stations will be indicated in order in accordance with the direction in which the car is traveling.

With the above and other objects in view, the invention consists in the novel construction, combination and arrangement of parts, as herein described, illustrated and claimed.

In the accompanying drawings: Figure 1 is a perspective view of an indicator embodying the present invention. Fig. 2 is a vertical longitudinal section through the same with parts shown in elevation. Fig. 3 is a vertical cross section through the same taken through the web containing drums. Fig. 4 is a face view of a portion of the web. Fig. 5 is an enlarged vertical cross section taken on the line $x-x$ of Fig. 6 through one end of the indicator casing showing the drum actuating mechanism in elevation. Fig. 6 is an enlarged fragmentary vertical longitudinal section showing the same mechanism as in Fig. 5. Fig. 7 is an enlarged detail elevation of the operating lever. Fig. 8 is a vertical longitudinal section through the same. Fig. 9 is an enlarged detail cross section illustrating the detachable mounting of one of the drum shafts. Fig. 10 is a detail perspective view of one of the detents and the operating means therefor.

In the preferred embodiment of this invention I employ a suitable casing or housing designated generally at A in which the indicating web and the operating means therefor are inclosed, said casing being pro-

vided at one end thereof with a door 1 to give access to the interior mechanism and the casing being further provided with suitable attaching lugs or ears 2 to enable it to be secured within a car in any convenient location. On its exposed side the casing A is provided with an observation window or panel 3 through which the indicating web hereinafter described is exposed as it is reeled from one drum to the other. The casing is also shown as provided with another smaller observation opening 4 through which is exposed a portion of another smaller web 5 upon which may be printed such words as East, West, North, South and the like to indicate the direction in which the car is moving, the web 5 being wound upon a pair of spools or rollers 6 and 7 the shafts of which project through a wall of the casing A, where they are provided with external knobs or handles 8 and 9 for a purpose readily understood.

The indicating web 10, a portion of which is shown enlarged in Fig. 4 has printed or otherwise represented thereon the names of the different stations or streets and it will be noted in Fig. 4 that the lines of indicating matter are spaced apart at progressively increasing or decreasing intervals so as to compensate for the differential movement of the web as it is wound upon or unwound from one drum or the other. The drums upon which the web 10 is wound are represented at 11 and 12 and arranged preferably one above the other and shown, for example, in Fig. 3. One end of the web is attached to one of said drums and the other end attached to the other drum preferably by a pin 13 or its equivalent the arrangement being such that the web may be detached from the drums when required. The web between the drums 11 and 12 passes around suitable guides 14 and 15 arranged above and below the observation opening or panel 3.

In the preferred embodiment of this invention, the shaft 16 of the lower drum 12 is mounted in bearings 17 in a bracket 21 and post 46 and is not removable, while the shaft 18 of the upper drum 11 is made removable, being for this purpose preferably squared as shown in Fig. 9 and removably fitted in a socket 19 of corresponding shape formed in the inner end of a stub shaft 20 which is journaled in a stand or bracket 21 located toward one end of the casing A adjacent to the door 1. A latch 22 serves to

retain the squared end of the shaft 18 in the socket 19, the latch being held in place by means of a spring 23 which permits the latch to be withdrawn to admit of the removal of the shaft 18. The opposite ends of the shafts 16 and 18 are stepped in bearings 24 at the opposite end of the casing A as shown in Fig. 2.

In addition to the detachable feature of the shaft 18, the upper drum 11 is journaled on its shaft 18 and is connected thereto by means of a coiled spring 25, one end of said spring being fastened to the shaft 18 at the point 26 and the other end of said spring being fastened at the point 27 to the drum 11, the arrangement being similar to an ordinary spring curtain shade roller, the object of this spring arrangement being to compensate for the wrappings of the web around the upper and lower drums to take up slack and prevent puckering or buckling of the web in operation.

The mechanism for operating the drums embodies a sprocket wheel 28 fast on the stub shaft 20, from which a sprocket chain 29 extends downwardly around another sprocket wheel 30 fast on the shaft 16. Fast on the same shaft 16 is a ratchet or notched wheel 31 adapted to be engaged and operated by either one of a pair of pawls 32 and 33 pivotally connected at 34 and 35 to the lower arm 36 of a two-armed lever which is journaled or fulcrumed upon the extended end portion of the shaft 16. The shorter arm 36 of said lever has pivotally connected thereto at 37 a rod 38 to the opposite end of which is attached a contractile spring 39 having its outer end connected to a fixed bracket or lug 40 on the inside of the casing A as shown in Fig. 5, the tension of the spring 39 being utilized to hold the lever in the position shown in Fig. 5. The operating lever is moved in the opposite direction by means of a rack bar 41 which has a jointed connection at 42 with the longer arm 36 of the operating lever, said rack bar 41 being in turn actuated by a pinion 43 against which the rack bar 41 is held by means of a backing roller 44. The pinion 43, as shown in Fig. 6 is mounted fast on a shaft 45 which extends through a bearing post 46 within the casing and has fast thereon an operating drum 47 around which is wrapped an operating cord or other flexible element 48, said cord extending outwardly through an opening 49 in a wall of the casing A so that it may extend downwardly within reach of the motorman or conductor.

Each of the pawls 32 and 33 is held in operative position by means of a spring 50 as best shown in Fig. 7 and in order to hold one of said pawls inactive while the other is in operation, each of said pawls is provided with a latch 51 which is shown as terminating in a pin 52 movable along a slot design-

nated generally at B in the longer arm 36 of the operating lever, the slot B comprising a longer branch 53 and a shorter branch 54. It will be understood by reference to Fig. 7 that when either one of the pawls 32 is to be thrown out of operation, the pawl 32 is pressed downwardly until the pin 52 travels along the longer branch 53 of the slot and enters the shorter branch 54. When left in this position, the pawl is held out of operative relation to the ratchet or notched wheel 31 while the other pawl remains in operation. This permits either of the pawls to be used according to the direction in which the indicating web is to be propelled.

Detents 55 and 56 are arranged at opposite sides of the wheel 31 and each of said pawls is mounted on an operating shaft 57 shown in Fig. 10, either of said pawls 55 and 56 being adapted to be thrown into or out of engagement with the notches or teeth of the wheel 31 according to the direction in which the web is moving, by means of a suitable operating handle or lever 58 at that end of the shaft 57 which lies between the bracket 21 and the door 1.

From the foregoing description, taken in connection with the accompanying drawings, it will now be understood that the indicating web 10 which is flexible, is wound upon the two drums 11 and 12 and that the compensating spring 25 always maintains the web in a taut condition, preventing the formation of any slack therein. It will also be understood that both of the drums are simultaneously operated by the sprocket and chain elements hereinabove described and that intermittent motion is imparted to one of said drums by the pawl and ratchet elements also described hereinabove. It will further be understood that the web may be propelled in either direction by means of the operating lever contained within the casing, said lever being actuated in one direction by the pull cord or element 48 and being retracted or moved in the opposite direction by the action of the spring 39. The door 1 gives access to the interior of the casing so as to admit of the removal and replacement of the indicating web and the upper roller 11 and also for the purpose of adjusting the reversing means consisting of the pawls 32 and 33 and the detents 55 and 56. Therefore, a pull on the cord 48 will propel the indicating web in either direction according to the adjustment of said pawls and detents. The progressively increasing or decreasing distances between the street or station designations on the flexible web or ribbon 10 insures the proper registration of the reading matter with and behind the observation panel 3 irrespective of the number of windings of said web on either of the drums 11 and 12.

It will be apparent that various changes

in the form, proportion and minor details of construction may be resorted to without departing from the spirit or sacrificing any of the advantages of the invention.

5 What I claim is:—

In a station indicator, a plurality of drums having parallel axes, means for transmitting rotary motion from one drum to the other, an indicating web wound upon said 10 drums and adapted to be reeled back and forth from either one to the other, and means for manually revolving one of said drums including a lever journaled on the

shaft of the last named drum, a rack bar extending from said lever, a pinion for operating said rack bar, pinion turning means, a lever retracting element, and pawl and ratchet elements between said lever and last named drum.

In testimony whereof I affix my signature 20 in presence of two witnesses.

RICHARD FRANKLIN AMERICA.
